UNITED STATES PATENT OFFICE.

WILLIAM R. JEAVONS, OF CLEVELAND, OHIO.

BLUE-FLAME OIL-BURNER.

SPECIFICATION forming part of Letters Patent No. 793,032, dated June 20, 1905.

Application filed February 25, 1904. Serial No. 195,293.

To all whom it may concern:

Be it known that I, WILLIAM R. JEAVONS, a citizen of the United States, residing at Cleveland, in the county of Cuyahoga and State of Ohio, have invented new and useful Improvements in Blue-Flame Oil-Burners, of which the following is a specification.

This invention relates to improvements in blue-flame oil-burners of the type which embody an oil-vaporizing trough or bowl surrounded by perforated combustion-tubes to produce a blue flame.

The primary objects, functions, novel arrangement of parts, and the advantages thereof will be embodied hereinafter.

In the accompanying drawings, Figure 1 is a longitudinal vertical sectional view of a one-burner stove which embodies my improvements. Fig. 2 is a relatively enlarged vertical sectional view of a burner trough or bowl, taken at right angles to Fig. 1 and which embodies my invention. Fig. 3 is a horizontal sectional view taken on the dotted line 3-3 of Fig. 1 looking in the direction indicated by arrow. Fig. 4 is a relatively enlarged detached perspective view of a burner trough or bowl, showing my present invention applied thereto. Fig. 5 is a detached perspective view of a modified form of screw-bearing for the oil-regulating valve.

Referring now to the drawings, 1 indicates any suitable or desired form of supporting-frame, and 2 an oil-supply. Connected with the oil-supply is what may be termed a "main" oil-supply pipe or duct 3.

4 is the oil-vaporizing trough. 5 represents the perforated combustion-tubes located above the said trough.

The foregoing parts and their operation whereby a blue flame is produced are well known and well understood in this art and need no further description, except as it may be necessary to explain my present improvements.

45 The form of oil-vaporizing trough or bowl is that disclosed in my Patent No. 706,064, dated August 5, 1902, and in which there is a transverse oil duct or channel, which is open at its upper end. My present invention pertains to an improved manner of supporting

the burner-trough and of arranging and operating an oil-controlling valve for the purpose of simplifying the construction of the parts, lessen the possibility of leakage, to present more satisfactory conditions for the 55 operation of the burner, and to afford convenient access to all parts of the device for cleaning purposes.

In my arrangement the burner trough or bowl 4 is provided with a clamp 8, which detachably clamps the trough to the periphery of the main oil-supply pipe 3. This clamp may be connected with the trough in any suitable manner and of any suitable form; but, as here shown, it is essentially U-shaped in 60 side elevation and is connected with the trough in a manner which I will now explain. A plug 9 is brazed or otherwise fixed to the bottom of the cross-duct 6 and preferably extends into the trough a short distance. This plug has a 65 vertical oil-passage 10 throughout its length, and the upper end of this passage has its wall formed into a valve-seat 11. The manner here shown of connecting the clamp 8 with the trough consists in providing the plug 9 with 70 external screw-threads 12. The upper arm of the clamp has a screw-threaded aperture 14 for receiving the screw-threaded portion of the plug 9. An opening 15 (preferably tapered) in the side of the pipe 3 receives the 75 tapered or conical lower end 16 of the plug 9. Formed in the lower side of the pipe 3 is a recess 17, which receives the upper tapered end of a clamping-screw 18, which passes through the lower arm of the clamp 8. The 80 recess 17 should be in accurate alignment with the opening 15 to support the trough 4 in a level position. From the foregoing it will be observed that the clamp comprises the U-shaped member 8, the plug 9, and the screw 18. 85

Main pipe 3 is usually the common iron or steel pipe of commerce, and for the purpose of insuring an oil-tight joint between the plug and the wall of the opening 15 the plug is made of a softer metal, preferably brass, 90 which is softer and more ductile than the metal of which the pipe is composed. By reason of this and the arrangement described the screw 18 pulls the tapered end of the plug firmly to its seat and, owing to the relative 95 100

yielding of the metal of which the plug is composed, conforms to any slight unevenness or inequalities of the wall of the tapered opening and insures an absolutely oil-tight joint.

In carrying out my invention a valve 20 passes vertically through the cross oil-duct 6 and coacts with the valve-seat 11 and by means of which the flow of oil from the main pipe 3 through the passage 10 to the oil-duct 6, and hence to the burner-trough, through passages 21 is entirely cut off or controlled, as desired. The valve-stem 20 is provided with a screw-threaded portion 22, which engages suitable coacting threads formed in a block 23, suitably secured between the walls of the duct 6, or the walls of the duct may be constructed for this purpose as shown at 24, Fig. 5. Carried by the upper end of the valve-stem is a disk or head 25, which is constructed to interlock with any relatively movable portion of the burner. As here shown, the disk or head is provided with a plurality of shoulders 26, with which one of the connecting-rods 27 of the combustion-tubes 5 is adapted to interlock, whereby a rotation of the combustion-tubes will correspondingly rotate the valve. As here shown, the combustion-tubes are adapted to be rotated through the medium of a surrounding drum 28, which may be connected in any desired manner with the combustion-tubes. In the form here shown the drum is separated from the combustion-tubes and is supported thereon by a suitable number of vanes 29, having shoulders 30 at their upper ends resting upon the upper ends of the combustion-tubes 5. This drum, with its vanes, is of such size that it is removable from the outer combustion-tube, yet when in position the turning of the drum will turn the tubes, the rotation of the tubes with the drum being assured by reason of the projecting ends of the rods 27, against which the vanes will abut in cases where the drum parts fit loosely over the perforated tubes. Projecting from the drum are a suitable number of handles 31, by which it is rotated.

The disk 25 is made to limit the amount of air which should enter the interior of the inner combustion-tube, as well as for the purpose of turning the valve 20. In the construction here shown the disk serves as an air-regulator, owing to its size as compared to the size of the opening through the center of the trough 4; but the disk may be made to accomplish this purpose in other ways, as will be readily understood by those skilled in this art.

With the arrangement as herein described every part of the interior of the oil-duct and oil-trough is readily accessible for cleaning. To remove small obstructions to the flow of oil, access can be had to the interior of the cross-duct 6 around the valve for dislodging

any dirt therearound without removing the trough from the pipe. By removing the trough all parts of the oil duct and valve can be reached to remove any carbon deposits or dirt. Furthermore, the valve is in such position that there is no chance for leaks and it very materially reduces the number of joints from a burner as ordinarily constructed. The construction does away with the usual soldered joints that can melt and become defective, and the structure is such that in case of any defective parts or accident a new oil-cup can be substituted by any unskilled person in a simple and efficient manner. To facilitate the detachment and attachment of the trough by unskilled persons, the clamping-screw 18 has its head provided with a transverse opening 18', adapted to receive a nail or a piece of wire by which it can be turned.

Where the clamp 8 is connected with the trough, as shown and described, it will be screwed tight to position to prevent any turning of the trough therein and the clamp will be made to fit sufficiently close to the pipe 3 to prevent any swiveling thereof. These results may be obtained, however, in other ways without affecting the essentials of my invention. It will also be observed that the upper end of the threaded aperture for the valve 20 is above the maintained level of the oil in the trough, so that a tight joint or a stuffing-box for the stem of the valve is unnecessary, which simplifies and cheapens the construction.

In operation the user regulates the flow of the oil to the trough, and thereby the size of the flame, by turning the combustion-section, which in turn rotates the valve. When desired, in the construction here shown the valve may be widely opened for flushing the oil-passages to remove slight obstructions, or the valve can be readily and quickly entirely removed for any desired purpose.

I do not desire to limit myself to the exact arrangement and construction of parts herein shown and described, for modifications in arrangement and construction can be made without departing from the scope and spirit of my invention so long as the essentials thereof are present.

The construction of the clamping feature 8 and its coacting parts forms no part of the invention which is made the subject-matter of this application or the patent to be issued thereon, because the said feature and its co-operating parts are the subject-matter of my United States Patent No. 775,903, dated November 22, 1904.

Having thus described my invention, what I claim, and desire to secure by Letters Patent, is—

1. A burner of the type described having a movable portion, in combination with an oil-feed duct for the burner, a controlling-valve for said oil-duct, the movable portion of the

- burner and valve being operatively connected and thereby adapted to move together.
2. A burner of the type described having a movable portion, in combination with an oil-feed duct for the burner, a controlling-valve for said oil-duct and surrounded by said burner, and an operative connection between said valve and the movable portion of the burner and thereby adapted to move together.
- 10 3. A blue-flame burner comprising a relatively movable vaporizing-trough and combustion-section, in combination with an oil-feed duct connected with the trough, a controlling-valve for said oil-duct, and an operative connection between the movable portion of the burner and said valve.
- 15 4. A blue-flame burner comprising an annular trough, a rotatable annular combustion-tube therefor, an oil-feed duct connected with the trough, a controlling-valve for said oil-duct and an operative connection between said valve and the rotatable combustion-tube.
- 20 5. A burner of the type described having a movable portion, in combination with an oil-feed duct connected with the burner, a controlling-valve for said duct, the valve and movable portion of the burner having operative interlocking members.
- 25 6. A blue-flame burner comprising an annular vaporizing-trough, a movable combustion-tube therefor, an oil-feed duct connected with the trough, a controlling-valve for said duct, the combustion-tube and valve having interlocking members.
- 30 7. A blue-flame burner comprising an annular vaporizing-trough, a rotatable and removable annular combustion-tube therefor, an oil-feed duct connected with the trough, a controlling-valve for the duct, the valve and removable rotatable combustion-tube having interlocking members.
- 35 8. A blue-flame burner comprising an annular vaporizing-trough having a transverse oil-duct, an annular rotatable combustion-tube therefor, an oil-feed duct communicating with the transverse duct, a controlling-valve arranged in the transverse duct, and an operative connection between the rotatable combustion-tube and said valve.
- 40 9. A blue-flame burner comprising an annular vaporizing-trough, a rotatable annular combustion-tube therefor, an oil-feed duct extending transverse said trough, and a controlling-valve for said duct concentrically located in respect to the trough and operatively connected with said rotatable tube.
- 45 10. A blue-flame burner comprising an annular vaporizing-trough, a rotatable annular combustion-tube therefor, an oil-feed duct for said trough, a controlling-valve for said duct, the combustion-tube having an extending member adapted to engage and rotate the valve when the tube is rotated.
- 50 11. A blue-flame burner comprising an annular vaporizing-trough, a rotatable combustion-tube therefor, an oil-feed duct for said trough, a controlling-valve for said duct surrounded by said tube, said tube having an inwardly-extending member adapted to engage and rotate the valve when the tube is rotated.
- 55 12. A blue-flame burner comprising an annular vaporizing-trough, two rotatable combustion-tubes therefor, an oil-feed duct for said trough, a controlling-valve for said duct surrounded by said tubes, and a rod passing through the tubes and adapted to rotate said valve when the tubes are rotated.
- 60 13. A blue-flame burner comprising an annular vaporizing-trough, an annular rotatable combustion-tube therefor, an oil-feed duct for said trough, a controlling-valve for said duct surrounded by said tube, the tube having an inwardly-extending member, and the valve having shoulders located in the path traveled by said member when the tube is rotated for rotating said valve.
- 65 14. A blue-flame burner comprising an annular vaporizing-trough, an annular rotatable combustion-tube therefor, an oil-feed duct for said trough, a controlling-valve for said duct, the combustion-tube having a transversely-arranged member, and the valve having vertically-arranged shoulders in the path traveled by said transverse member.
- 70 15. A blue-flame burner comprising an annular trough, annular combustion-tubes therefor, an oil-feed duct for said trough, a controlling-valve for said duct surrounded by said trough, a disk carried by the valve and partially closing the air-passage through said trough, and also constituting means by which the valve is controlled.
- 75 16. A burner comprising an annular vaporizing-trough, an annular combustion-section therefor, an oil-feed duct for said trough, a controlling-valve for said duct surrounded by said trough, a rotatable drum surrounding said combustion-section, and an operative connection between said drum and said valve.
- 80 17. A blue-flame burner comprising an annular vaporizing-trough, annular combustion-tubes therefor, a drum surrounding said tubes, an oil-feed duct for said trough, a controlling-valve for said duct, and members passing through said combustion-tubes and adapted to interlock with the valve and with said drum.
- 85 18. A removable burner-trough having a transverse oil-duct, said duct having a valve-seat in its bottom, the duct having a screw-threaded aperture above and in alignment with said seat, the valve having its lower end adapted to control said seat and provided with a screw-threaded portion engaging said screw-threaded aperture, whereby the valve and its seat are removable with the trough.
- 90 19. A blue-flame burner comprising an annular vaporizing-trough, a rotatable combus-

tion-section therefor, an oil-duct connected with said trough, a controlling-valve therefor, the valve and combustion-section operatively connected, and means carried by the 5 combustion-section for rotating it and thereby the valve.

In testimony whereof I have hereunto set

my hand in the presence of two subscribing witnesses.
